UNITED STATES PATENT OFFICE.

THOMAS SPENCER JAMES, OF PECKHAM, LONDON, ENGLAND.

FOUR-CYCLE INTERNAL-COMBUSTION ENGINE.

1,104,804.

Specification of Letters Patent. Patented July 28, 1914.

Application filed June 13, 1913. Serial No. 773,551.

To all whom it may concern:

Be it known that I, THOMAS SPENCER JAMES, a citizen of the United Kingdom of Great Britain and Ireland, and resident of 5 16 Edith road, Peckham, London, England, have invented certain new and useful Improvements in and Relating to Four-Cycle Internal-Combustion Engines, of which the following is a specification, such as will enable others skilled in the art to which it 10 pertains to make and use the same.

This invention relates to internal combustion engines of the piston and cylinder type and in particular to improved means for 15 causing the piston to travel farther rearwardly when on the exhaust stroke than it does upon the other strokes, the primary object of the invention being to completely evacuate the cylinder of all burnt gases and 20 to increase the suction stroke so as to draw in greater charge of combustible gas than is usual. The throw of the other two strokes of the piston necessary to complete the cycle of operations, namely compression and firing, are preferably the same and as usual. The piston rod has a telescopic action and is caused to increase and decrease its length as 25 by means of a drum around the rod upon which drum is a cam track, the said drum being rotated by means of two toothed wheels one integral with the drum and the other on the crank of the engine.

I will now describe my invention with reference to the accompanying drawings which 35 show a construction in which the said drum and cam wheels are employed.

Figure 1 shows the engine in elevation the cylinder and crank case being indicated by plain lines and the drum and some of the 40 parts being shown in section, while Fig. 2 is a development of the cam track.

The cylinder and crank case *a* is of usual type as is also the piston *b* and the crank pin *c* and axle *d*. The connecting rod is of 45 compound and telescopic construction and consists of two parts *e* and *f* of which *e* is connected at *e'* to the piston in usual manner while the part *f* which telescopes within the part *e* is connected to the crank pin bearing 50 the arrangement being such that the parts *e* and *f* move in relation to each other. The lower end of the part *e* is increased in diameter to receive a drum *g* in which the cam track *h* is made. A screw *i* provided with a 55 roller *j* is fitted within the lower end of the part *e* so that the said roller travels in the

cam track *h* while the to and fro movement of the part *e* on the part *f* is permitted by the side slots *k* in which the pins *l* travel. The lower end of the drum is furnished 60 with a bevel wheel *m* which is in constant mesh and is driven by a smaller bevel wheel *n* secured on the crank pin.

In this drawing the piston is shown by full lines in its normal rearward position 65 but it will be obvious that as the engine rotates, the wheel *m* will drive the wheel *n* and thus turn the cam drum *g* which will have the effect of lifting the roller and thus raising the sleeve part *e* and increasing the 70 distance between the crank pin and the gudgeon pin *e'* thereby thrusting the piston farther back within the cylinder as shown by the dotted lines and it will be seen from Fig. 2 that while a large part of the cam 75 track *B* is straight the curved portion *A* will raise the piston to this maximum rearward position every fourth stroke and it will be thus clearly seen that the engine having been adjusted, and this stroke being the 80 exhaust stroke, the whole of the burnt gases will be expelled and because the next outward stroke is the suction stroke a larger volume of combustible gases will be drawn in.

The engine illustrated is shown without 85 valves and other parts, and as to my invention, without details whereby one part can be adjusted in relation to another but it will be understood that such of these parts as are necessary are employed and that the invention 90 can be carried out in several manners within the scope of the following claims.

What I claim and desire to secure by Letters Patent is:—

1. In an internal combustion engine, the 95 combination of a cylinder, piston and crank shaft, a telescopic piston rod connecting the crank shaft and piston, means including a rotating element operable with and mounted on the telescopic shaft to separate and expand the telescopic shaft, whereby to cause the piston to travel farther outwardly on the exhaust stroke than it does on the other strokes in the cycle of operation, and means 100 on the crank shaft for operating the rotating element.

2. An internal combustion engine having a telescopic piston rod, a crank pin a pinion on the crank pin, a pinion co-axial with the piston rod and meshing with the piston 110 on the crank pin, a drum connected to the pinion and having in it a cam track, and a

projection on one member of the telescopic piston rod to engage the cam track and increase the throw of the piston.

3. An internal combustion engine having 5 a telescopic piston rod comprising inner and outer parts a crank pin, a drum within the outer part, said drum having in it a cam track and fixed to it a pinion, a roller mounted upon the outer part of the piston 10 rod adapted to travel in the cam track, pins in the inner part of the piston rod adapted to travel slots in the outer part of the rod and a pinion on the crank pin adapted to drive the pinion on the drum.
- 15 4. An internal combustion engine having a piston furnished with a telescopic rod comprising inner and outer parts adapted to slide one on the other a crank pin, slots in the outer part, pins projecting from the inner part into the said slots, a pinion coaxial with the piston rod and having on it a drum provided with a cam track in which a roller carried by the outer part of the piston rod is adapted to travel and a pinion on the crank 25 pin adapted to drive the pinion having the drum.

5. In an internal combustion engine, the combination of a cylinder, piston and crank shaft, means including a telescopic piston 30 rod and cam thereon interposed between the crank shaft and piston to cause the latter to make a longer stroke outwardly when exhausting the burnt gases than it does when making the other strokes in the cycle of 35 operation, and means for operating the cam.

6. In an internal combustion engine, the combination of a cylinder, piston and crank shaft, of a telescopic piston rod connecting the crank shaft and piston, and means including gears operated by the crank to separate the telescopic piston rod to increase 40 the outward movement of the piston rod on the exhaust stroke of the engine.

7. In an internal combustion engine, the combination of a cylinder, piston and crank shaft, a telescopic connecting rod between the crank shaft and the piston, means including a device interposed between the telescopic members of the piston rod to increase 45 one outward stroke in a series of strokes of the piston, and means operated by the crank shaft for actuating the first mentioned means.

8. In a four cycle internal combustion engine, the combination of a cylinder, piston 50

and crank shaft, a connecting rod between the crank shaft and the piston, means including a rotatable cam for causing the piston to travel farther outwardly on its exhaust stroke than it does on the other strokes 60 in the cycle of operation, and means operated by the crank shaft for rotating the cam.

9. In an internal combustion engine, the combination of a cylinder, piston and crank 65 shaft, a telescopic connecting rod between the crank shaft and the piston, said connecting rod comprising two members, one of which is formed with slots and the other of which is provided with pins to engage said 70 slots, a drum inclosed in one of the telescopic members, said drum having a cam track, a projection on the inclosing telescopic member to engage the cam track, a gear on the drum, and a gear on the crank 75 shaft to engage the gear on the drum, whereby to cause the cam to increase the outward throw of one stroke in a series of strokes of the piston.

10. In an internal combustion engine, the 80 combination of a cylinder, piston and crank shaft, a telescopic connecting rod between the crank shaft and the piston, said connecting rod comprising two members, one of which is formed with pins to engage said 85 slots, a drum inclosed in one of the telescopic members, said drum having a cam track, a projection on the inclosing telescopic member to engage the cam track, and means on the crank shaft for operating the 90 drum to cause the cam track to increase one of a series of outward movements of the piston.

11. In a four cycle internal combustion engine, the combination of a cylinder, piston 95 and crank shaft, a piston rod connecting the piston and crank shaft, and means for causing the piston to travel farther on its outward exhaust stroke than it does on the other outward stroke and to cause said piston 100 to travel farther on its inward gas intake stroke than it does on the other inward stroke.

In witness whereof I have hereunto set my hand in presence of two witnesses. 105

THOMAS SPENCER JAMES.
